UNITED STATES PATENT OFFICE

2,359,093

POINTER FOR PENCIL LEAD

Nathaniel Eastman, New York, N. Y.

Application January 4, 1944, Serial No. 516,965

4 Claims. (Cl. 120—94)

This invention relates to a pointer for pencil lead and is designed primarily for use by architects and others requiring sharp points on pencil lead in order to execute their work properly.

An object of the invention is to provide a simple, compact and inexpensive structure into which the sharpened end of a lead pencil can be inserted and brought to position where the exposed portion of the lead will be subjected to a wiping action by an abrasive material, thereby bringing the lead to a fine point and at the same time producing a dust which subsequently can be used for touché work.

A still further object is to provide a structure in which the abrasive material can be kept substantially free from accumulations of powdered lead so that it will constantly produce efficient service over a long period of time without necessitating any change.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a front elevation of the device.

Figure 2 is a top plan view.

Figure 3 is a longitudinal section through the housing portion of the structure, the abrasive belt and other parts of the mechanism therein being shown in elevation and a portion of the standard being also shown in elevation.

Referring to the figures by characters of reference, 1 designates the lower portion of a substantially ovoid housing which can be formed integral with a support 2 or can be attached thereto if desired. The upper portion of the housing is formed preferably of a plastic material and has been indicated at 3. The upper edge portion of the lower section 1 is offset to provide a seat 4 extending lengthwise of the edge and this seat is adapted to be engaged by the corresponding edge of the top portion 3. This top portion is slightly oversize so that it can be flexed to snap into position on the seat and thus be held assembled frictionally with the lower section of the housing. The two sections cooperate to provide an inlet opening 5 at the

small end of the housing and this opening is of sufficient size to receive a lead pencil.

Journalled within the lower section of the housing adjacent to the respective ends thereof are shafts 6 and 7 one which are mounted rolls 8 and 9. An endless belt 10 is mounted on the rolls and has an abrasive surface 11. The axes of the two shafts 6 and 7 are in a plane which is inclined relative to the housing so that the upper flight thereof is extended upwardly and rearwardly away from a point adjacent to the lower portion of the opening 5 and will intersect the central, longitudinal axes of the housing.

Extending transversely of and journalled in 15 the housing at a point between the shafts 6 and 7 and between the upper and lower flights of the belt 10 is a shaft 12 having a finger 13 affixed thereto and rotatable therewith. This finger constitutes a tappet which is adapted to intermittently strike the lower flight of the belt 10 at a point between the rolls 8 and 9. For this purpose of effecting this operation, an arm 14 is extended from shaft 12 into the path of a tripping finger 15 which is secured to and rotates with the shaft 6. Both the arm 14 and the tripping finger 15 are located beyond the sides of belt 10 so that they are free to operate without interference by the belt.

By means of a crank arm 16 or the like secured 30 to shaft 6 and located outside of the housing, the said shaft can be rotated by the user so as to cause the belt to travel in the direction indicated by the arrow in Figure 3. Thus when a pencil having a portion of its lead exposed, is inserted through opening 5 into the housing, said exposed portion of the lead can be caused to bear upon the abrasive upper surface of the top flight of the belt so that as the belt moves relative thereto, it will exert a wiping action upon the lead. By slowly 35 rotating the pencil during this action, the lead can be brought to an extremely sharp point. The pulverized lead which is removed in this way is collected in the lower section 1 of the housing and, as before stated, can be subsequently used 40 for touché work.

As the belt is operated in the manner described, the tripping finger 15 intermittently engages and lifts the arm 14 so as to raise the tappet 13 out of contact with the lower portion of the belt 10. 45 Thereafter these parts are released and will fall by gravity back to their normal positions so that the tappet thus will strike the belt and dislodge any fine particles of lead which may be adhering thereto.

50 It will be noted that that portion of the tappet

which engages the belt is in the form of a shoe having an upturned end 17 so that the belt can wipe along the shoe without injury thereby during pauses in the operation of the tappet.

By slightly contracting the upper section 3 of the housing the same can be disengaged from its seat along the top edge of the lower section of the housing so as thus to expose the contents of the structure and permit convenient removal of the accumulated dust.

What is claimed is:

1. The combination with a housing having a pencil inlet at one end, of an inclined endless belt movably supported in the housing and positioned for engagement by the exposed end portion of the lead of the pencil, means for operating the belt, and means actuated by the movement of the belt for intermittently agitating the belt.

2. The combination with a housing having an opening for the reception of a pencil having exposed lead at one end, of a belt supported in the housing and having an abrasive surface, said belt having one flight inclined relative to the axis of the pencil-receiving opening thereby to present an inclined abrasive surface to the exposed portion of the lead, means for actuating the belt, and means operated by the movement of the belt for intermittently tapping a portion of the belt.

3. A device for pointing the lead of a pencil and accumulating lead dust for touche work,

30

which includes a housing having an opening proportioned to receive a pencil a portion of the lead of which is exposed, an endless belt in the housing, means for movably supporting the belt with one surface thereof inclined relative to the inserted pencil, means for actuating the belt along and longitudinally of the exposed portion of the lead, said belt having an abrasive surface for contacting the lead, and means for operating the belt.

4. A device for pointing the lead of a pencil and accumulating lead dust for touche work, which includes a housing having an opening proportioned to receive a pencil a portion of the lead of which is exposed, an endless belt in the housing, means for movably supporting the belt with one surface thereof inclined relative to the inserted pencil, means for actuating the belt along and longitudinally of the exposed portion of the lead, said belt having an abrasive surface for contacting the lead, means for operating the belt, a tappet mounted for oscillation in the housing and surrounded by the belt, a tripping element movable with the belt-operating means, and means actuated by said element for intermittently lifting and releasing the tappet, said tappet being normally in engagement with a portion of the belt.

NATHANIEL EASTMAN.
